UNITED STATES PATENT OFFICE.

JOHN E. CAME, OF BOSTON, MASSACHUSETTS.

DESIGN FOR A BILLIARD-TABLE.

Specification forming part of Design No. 7,789, dated October 6, 1874; application filed August 5, 1874.
[Term of Patent 7 years.]

To all whom it may concern:

Be it known that I, JOHN E. CAME, of Boston, in the county of Suffolk and State of Massachusetts, have invented a Design for a Billiard-Table, of which the following is a specification:

The nature of my design is fully represented in the accompanying illustration, to which reference is made.

A is the bottom part of the frame or table, inclining or beveling inward. Between the top rail *a* of the table and the legs *B*, the incline or bevel of the frame is ornamented with longitudinal bars *b* and cross-bars *c*, which intersect each other and project from the incline face, the whole giving a very unique and novel

appearance to the table. The bars referred to in the preceding description I prefer to bevel or chamfer at their edges; and, by having the bars walnut and the body of the table ash, or vice versa, the effect and contrast is most pleasing.

Having thus described my improved design, what I claim, and desire to secure by Letters Patent, is—

The design for a billiard-table, substantially as shown and described.

JOHN E. CAME.
